[57] CLAIM

The ornamental design for a combined syringe barrel, needle hood and cap therefor, substantially as shown and described.

DESCRIPTION

FIG. 1 is a perspective view of a combined syringe barrel, needle hood and cap therefor showing my new design;

FIG. 2 is a side elevation view thereof;

FIG. 3 is a right end elevational view thereof;

FIG. 4 is a left end elevational view thereof;

FIG. 5 is a perspective view of a modified embodiment thereof showing a reduced barrel;

FIG. 6 is a side elevational view of FIG. 5;

FIG. 7 is a right side elevational view of FIG. 5;

FIG. 8 is a left side elevational view of FIG. 5;

FIG. 9 is a side elevational view of the cap for the needle hood;

FIG. 10 is an enlarged fragmented right end perspective view showing the inside of the cap of FIG. 9;

FIG. 11 is a right end elevational view of FIG. 9;

FIG. 12 is a left end elevational view of FIG. 9;

FIG. 13 is a side elevational view of the needle hood;

FIG. 14 is a perspective view of the needle hood of FIG. 13;

FIG. 15 is a right end elevational view of FIG. 13; and

The cap and needle hood are separately shown in FIGS. 9-16 to show to more completely show their detail.
